COMB LOCK ASSEMBLY

Carl O. Bruestle, Rahway, N. J., assignor to Borg-Warner Corporation, Chicago, Ill., a corporation of Illinois

Application October 25, 1943, Serial No. 507,581

8 Claims. (Cl. 140—3)

This invention relates to weaving machines and the like, and it is directed primarily to the provision of improvements in the weaving head for such weaving machines as those used for weaving metallic screen cloth such as that disclosed in United States Patent No. 2,194,222, issued to W. B. Ewing.

It has been found that in weaving machines heretofore available for weaving metallic screen cloth and the like, such as machines of the type shown in United States Letters Patent No. 2,223,317, issued to W. B. Ewing, November 26, 1940, the comb assembly of the weaving head vibrates upon its return to a position closest to the quill assembly instead of properly seating in the position intended. This vibration is due, among other things, to the forces developed in the comb assembly by the movement of the operating cam roller over the surface of the cam, and particularly to the fact that change from the rise to the dwell of the cam is rather abrupt and rapid.

This vibration of the comb assembly has a distorting effect on the fabric being woven, which is particularly objectionable in certain types of screen cloth such as that above-mentioned, and it also has the effect of pounding the comb assembly against the quill assembly, battering the ends of the quill and damaging them. The vibration and battering likewise cause excessive wear of the affected and related parts of the machine.

It is the principal object of this invention to provide a construction which will minimize or entirely prevent the above-mentioned objectionable vibration.

In this connection, it is an object to provide a locking means catching and locking the comb assembly in the position desired the instant it is returned to that position by movement of the cam roller from the rise to the dwell of the cam, whereby vibration sufficient to distort the screen cloth and batter the quills, or either, is substantially damped or entirely prevented.

It is an object of the present invention to provide a construction in which the movement of the comb assembly away from the quill assembly in each cycle of operation is initiated by a cam roller moving from the dwell to the rise of a plate cam, but in which the cam roller is held to the plate cam by force of a spring and thereby the comb assembly is returned by spring force to the desired position with respect to the quill assembly and frame of the weaving machine as the cam roller moves from the rise to the dwell of the cam and to provide a locking means in which the comb assembly is locked in the predetermined position

adjacent to the quill assembly as the cam roller completes the movement from the rise to the dwell by a locking means which automatically releases after danger of such vibration, so as not to interfere with the subsequent cycle of operations.

It is a further object to disclose a new comb assembly lock for preventing vibration of the comb assembly with reference to the quill assembly by means including an auxiliary roller which is adjustable, an internal arcuate segmental cam engaging said roller, a reciprocating plate type cam which initiates the desired movements of the comb assembly, and a cam roller bearing on said reciprocating plate cam.

It is a further object of the invention to provide a construction which is easily assembled, which is readily adjustable, and one which is comparatively inexpensive.

Other objects, the advantages and uses of the invention will become more apparent after reading the following specification and claims, and after consideration of the drawings forming a part of the specification, wherein:

Fig. 1 is a fragmentary cross-sectional side elevational view of the portion of a weaving machine generally referred to as the weaving head assembly;

Fig. 2 is a fragmentary rear elevational view of a portion of the device of Fig. 1, looking toward the front as indicated by the arrow of Fig. 1; and

Fig. 3 is a view similar to Fig. 2 but illustrating a cam mechanism used for driving the quill operating means.

Referring more in detail to the construction shown in the drawings, there is provided what may be termed the weaving head assembly having the frame 22, the base portion 24, the comb assembly 26, and a driving means (not shown) but represented by the drive shaft 28.

The frame 22 preferably carries the quill assembly 30, which quill 30 is operated by the rack 32, which rack in turn is driven by the rack arm 34. The rack arm 34 is journaled to the frame 22 as indicated in Fig. 1, and has a reciprocating motion imparted by the drum cam 36 (see Fig. 3).

The comb assembly 26 is carried by a support arm 38 which preferably is an integral part of the web 40.

The support arm 38 and the integral web 40 are movable about the axle 42, on which they are journaled, and they are held in place on said axle by means of the member 44 and bolt 46, in a manner which will be apparent from Fig. 1.

The web 40 (see Figs. 1 and 2) also has a bracket portion 48 which preferably is integral

with said web 40, and which extends upwardly and has an overhanging ledge portion, as shown.

Attached to the bracket 48 by means of bolts or the like 50 is a link 52, which is adjustable longitudinally with respect to the bracket 48. For this purpose the link 52 may be provided with the slot shaped bolt holes 54, as is clearly apparent from the drawings, through which the bolts 50 pass, and by means of which the link is adjustably retained on the bracket 48. The set screw assembly 56 passes through the bracket 48 and seats against the links 52, aiding the bolts 50 in holding said link 52 in longitudinal adjustment with respect to the bracket 48.

The bracket 48 carries the cam roller shaft 58. This roller shaft 58 is preferably in the form of a bolt having a head portion 60, and a nut 62, which latter is threaded on to the end of the roller shaft 58.

The roller shaft 58 forms the axle for the lock roller 64, and is preferably offset or eccentric a small amount, for example, $\frac{1}{2}$ of an inch, in the portion which supports said lock roller 64. This is so that the lock roller 64 may be readily adjusted to compensate for wear of the parts as will hereinafter be explained.

The roller shaft 58 also carries the cam lift roller 66, which is preferably spaced very slightly from the lock roller 64. The reason for this spacing is that the cam lift roller 66 and the lock roller 64 will normally rotate in opposite directions, and by so spacing them, friction between them will be avoided. The link 52 with its rollers 66 and 64 constitutes a follower assembly for cams 68 and 76.

The cam lift roller 66 normally engages the plate cam 68 (see Figs. 1 and 2), which has the dwell portion 70 and the rise portion 72.

The spring 74, carried by the frame 22 normally exerts a downward pressure on the web 40 and therethrough on the bracket 48 and cam lift roller 6. This ordinarily retains cam lift roller 66 in close engagement with the dwell and rise portions of the surface of the cam 68. It is noted however that the rise 72 is rather abrupt, and that when the cam lift roller 66 leaves the rise 72 it does so with a quick drop which causes the parts, including the web 40, the support arm 38, and the comb assembly 26 to vibrate.

This vibrating action is accentuated by the fact that the parts, while fairly well balanced, are comparatively heavy, and any force which throws them off balance will be reflected to the spring 74 in the form of vibration, which will cause the spring 74 to vibrate, and the comb assembly will also be vibrated therewith. By means of high speed moving pictures, and by other means it has been determined that the comb assembly will vibrate at least 7 or 8 and possibly more times each time the follower drops from the rise 72. This vibration, as pointed out in connection with the objects, seriously batters the quills 30, and also has a tendency to distort the woven material (which, during the time such vibration normally occurs, undergoing a "tying" operation by the rotation of the quills 30). Any such distortion, however small, in a screen cloth of the type mentioned, is a serious matter and must be prevented if possible. For this purpose I have provided a locking means of which the lock roller 64 is a part, for the purpose of preventing this vibration.

Carried by the shaft 28, and keyed to rotate with the plate cam 68, is an internal arcuate segmental cam 76. This cam 76 is adapted to

engage the lock roller 64 the instant the roller 66 moves from the rise 72 to the dwell 70 of the cam 68. This engaging action catches the web 40 with its attached brackets and the comb assembly 26 carried thereby at said instant of completion of change, and exerts a holding action on these parts against vibration. This holding action is caused by the engagement of the lock roller 64 with the interior cam 76 which restrains or prevents upward movement of the follower, and by the engagement of the lift roller 66 with the plate cam 68, which holds the follower against downward movement. This holding action against upward movement continues for only a fraction of the circumference of the cam 68, after which the internal cam 76 rides out of engagement with the lock roller 64, and the web assembly 40 is released. The lift roller 66 is then free to lift the web assembly 40 up on the rise 72, initiating another cycle of movement for the comb assembly 26.

As was indicated above, the lock roller 64 is adjustable with respect to the internal cam 76 by means of rotating or positioning the bolt or shaft 58. This shaft 58, as was indicated above, is preferably slightly eccentric and the roller may be adjusted a sufficient amount by rotation of said eccentric shaft 58 to assure close engagement with the cam. The link 52 is adjustable 30 with respect to the bracket 48 to position the comb assembly 26 with respect to the quill means by means of the bolts 50 and the set screw assembly 56.

For the purposes of illustration, it is noted that 35 the comb assembly 26 includes a slide block member 78 which carries a front comb 80, and the comb assembly 26 also includes a back comb 82. The front comb rides on the back comb 82 and is movable by the movement of the slide block 78. 40 Slide block 78 is moved by an arm 100 which is under control of the second plate cam 36 through the medium of the roller 88 and follower member 90, against which member 90 said arm 100 bears and with respect to which it is adjustable by means of a set screw 92.

The cams 68, 76, 86 and 36 are all preferably driven by the shaft 28 to which they may be keyed or otherwise fastened.

While I have described my invention in connection with certain specific embodiments thereof, it is to be understood that this is by way of illustration rather than limitation and that the invention is to be defined by the appended claims which should be given a scope as broad as commensurate with the prior art.

I claim:

1. In a weaving machine, a quill means, comb means movable with respect to said quill means and operating on a cycle of movement performing with said quill means certain weaving operations, means moving said comb means in said cycle of operations, said moving means normally causing said comb means to vibrate at one portion of each said cycle of operation, and means at least substantially damping said vibrations while leaving said comb means free to move in said cycle of operations.

2. In a weaving machine for weaving metallic screen cloth, comb assembly means, quill means, means causing a cycle of relative movement between said comb assembly means and said quill means, and means substantially preventing vibration upon completion of said cycle of relative movement, without interfering with said relative movement.

3. In a weaving machine for weaving metallic screen cloth, comb assembly means, quill means, means causing a cycle of relative movement between said comb assembly means and said quill means, and means substantially preventing vibration upon completion of said cycle of relative movement, without interfering with said relative movement, said preventing means comprising a pair of cam actuated rollers, in connection with the means causing the cycle of relative movement above-mentioned, one of which rollers engages an internal, segmental arcuate cam preventing movement for vibration in one direction following said portion of relative movement first above-mentioned, said second roller engaging a second cam preventing vibrating movement in the other direction.

4. In a weaving machine, a frame means, a quill means carried by said frame means, a comb assembly journalled on said frame means and movable with respect to said quill means, means connected to said comb assembly successively moving said comb assembly means in a plurality of positions with respect to said quill means during a weaving operation, said moving means normally causing vibration of said comb assembly means in a position damaging said quill means and interfering with said weaving operation, and means substantially preventing said vibration in said position.

5. In a weaving machine of the class described, a frame means, weaving quill means carried by said frame means, a comb assembly means carried by a support arm, said support arm being journalled on said frame means for movement of said comb assembly with respect to said quill means, means comprising a web carried by said support arm and movable therewith to move the comb assembly for a series of weaving operations, means defining a bracket integral with said web, cam engaging means adjustably carried by said bracket, cam means engaged by said cam engaging means whereby said web and said comb assembly means are caused to move in performing the weaving operations, a second cam engaging means carried by said bracket, a second cam means engaging said second cam engaging means during a fraction of the interval, said first cam engaging means engages said first-mentioned cam, and thereby locking said comb assembly means with its support arm web and bracket means against objectional vibration with respect to said quill means.

6. In a weaving machine of the class described,

a frame means, weaving quill means carried by said frame means, a comb assembly means carried by a support arm, said comb assembly means and support arm being journalled for movement with respect to said quill means, means in connection with said comb assembly means causing said comb assembly means to move as above mentioned in carrying out a cycle of weaving operations, said last mentioned means including a cam engaging means and a cam means engaged thereby, and means in connection with said cam engaging means comprising a second cam engaging means, a second cam engaged by said second cam engaging means, said second cam and second cam engaging means operating to lock the comb assembly means against undesired vibration during the weaving operation.

7. In a weaving machine of the class described, a frame member, a comb assembly, said comb assembly being supported by said frame means, and movable with respect to said frame means, means comprising a web integral with said comb assembly, a cam engaging roller carried by said web, cam means comprising a plate cam engaging said roller and actuating the movement of said comb assembly means through its weaving operations, and means comprising a second cam engaging means in connection with said web means, and means comprising an internal, segmented, arcuate cam engaging said second mentioned roller upon completion of the cycle of movement of said comb assembly means, the arrangement being such that said second mentioned cam and roller means lock the comb assembly against objectional vibration due to the action of said first mentioned cam.

8. In a weaving machine of the class described, a frame member, a comb assembly, said comb assembly being supported by said frame means, and movable with respect to said frame means, means comprising a web integral with said comb assembly, a cam engaging roller carried by said web, cam means comprising a plate cam engaging said roller and actuating the movement of said comb assembly means through its weaving operations, and means comprising a second cam engaging means in connection with said web means, and means comprising an internal, segmented, arcuate cam engaging said second mentioned roller upon completion of the cycle of movements of said comb assembly means, said second cam engaging roller being adjustable with respect to said second mentioned cam means.

CARL O. BRUESTLE.
